UNITED STATES PATENT OFFICE.

JOHN GEORGE BARNES, OF HARROGATE, ENGLAND.

DETACHABLE HEEL.

1,019,585.

Specification of Letters Patent.

Patented Mar. 5, 1912.

Application filed April 11, 1911. Serial No. 620,320.

To all whom it may concern:

Be it known that I, JOHN GEORGE BARNES, of 38 Leeds road, Harrogate, in the county of York, England, have invented new and useful Improvements in Detachable Heels, of which the following is a specification.

This invention relates to improvements in that type of interchangeable heels and top pieces for the same,—both of which are hereinafter termed and included in the term “top pieces” for boots and shoes,—in which as the top pieces become worn down on one side can be changed from one boot to the other, whereby the heels are always kept straight,—or nearly so,—and the boots kept in good order to the end. When the top pieces are completely worn out they can be discarded and new ones substituted which may be attached by the wearer, thereby obviating the necessity of sending the boots or shoes to a boot repairer.

Heretofore it has been proposed to provide top pieces which are connected with the main portion of the heel by various means, but considerable difficulty has been experienced in securing a construction which may be readily and conveniently detached, or placed in position, and a construction which would stand up satisfactorily in use.

The object of the present invention is to overcome these difficulties heretofore found in devices of this nature, and consists, generally, in providing a two-part plate or member so arranged and inclosed that the plate will exhibit only a single thickness when in place, provision being made for securing the parts against said plate, and from lateral movement.

More specifically, in carrying this invention into practice, a sheet metal plate is provided which is attached to the main portion of the heel, and which has a portion thereof cut away so as to provide an opening having parallel marginal edges or sides to receive a slide plate, provision being made for securing this sliding plate in place to hold the sections of the heel together.

In the drawings hereunto annexed I have shown two methods for carrying this invention into practice, in which—

Figure 1. is a front elevation of a plate suitable for fixing to the main portion of the heel provided with a recess extending from the rear of the heel; Fig. 2. is a sectional elevation on line A, B, Fig. 1; Fig. 3. is an elevation of a sliding plate which fits

into the recess shown at Fig. 1; Fig. 4. is a sectional elevation on line C, D, Fig. 3; Fig. 5. is an end elevation of Fig. 3; Fig. 6. is an elevation showing two plates together; Fig. 7. an end elevation of the same; Fig. 8. a transverse section on line E, F, Fig. 6; Fig. 9. a sectional elevation of a heel with detachable plates shown in full and constructed according to this invention; Fig. 10. a diagrammatic view showing the position of the two plates when detached from the heel or portion thereof in order to pass over and lock with the tapering pins; Fig. 11. an elevation of the main portion of a heel with the fixed portion of the plate secured thereto; Fig. 12. an elevation of a detachable top piece of a heel with the sliding plate fixed thereto; Fig. 13. a sectional elevation of the heel and with the detachable plates shown in full applied in the same manner as at Figs. 11 and 12; Fig. 14. is a front elevation of a detaching tool; Fig. 15. a side elevation of the same.

Like parts in all the views are marked with similar letters of reference.

a is the main portion of a boot or shoe heel which is built up in any desired number of layers of suitable material, or of wood and it is provided with a detachable top lift *b* consisting of one or more layers. The heel may be formed in the ordinary manner and is fixed to the lasted upper by any suitable and ordinary means.

To the upper surface of the main portion *a* of the heel is fixed in Fig. 9,—or to the detachable top *b* as in Figs. 12 and 13,—by any suitable means, such as rivets, or screws, a plate *c* formed of sheet metal, say about 24 B. W. gage. The plate *c* is made of the same size and contour as the heel to which it is to be attached so as to cover the outer flat surface of the same. In the plate is formed a recess hereinafter termed an “opening” *d* by cutting away a portion of the plate. The recess as shown at Fig. 1. extends from the back or rear of the heel inward to within a suitable distance of the breast *e* of the heel, thus providing an opening *d* with parallel sides *f*, and also leaving a strip *c* of metal at the front of the plate. The opening *d* may or may not be slightly enlarged in an angular direction at or near its inner end *g*. The opening is also enlarged at *h* for a suitable distance from the rear of the heel inward so as to permit of the sides *f* being turned slightly upward

and thus form a slide for a second plate to be hereafter described. The sides or walls of the enlargement h of the opening also form stops for preventing any side play of 5 the second plate at its rear. At the breast of the heel are provided a number, say, two or more, slightly tapering pins i , which are arranged to be riveted to the plate, and also to project a suitable distance above its upper 10 surface. The pins i are fixed at a suitable distance from the breast of the heel as well as from each other. The pins i may, or may not, be slightly chamfered on their rear upper edges. A second piece of metal 15 j of the same thickness as the plate c is provided and made in two widths, that is to say, the larger portion is provided with parallel sides k which extend from the rear of the plate to within a suitable distance of 20 its breast and recessed portion. The parallel sides k are inclined or tapered, as shown at Figs. 3 and 5 for a portion of their length so as to fit in and slide under the parallel edges f of the plate c , as shown 25 at Fig. 8, thus leaving a plain or portion at the rear of plate j which fits into the space between the sides h of plate c so as to be level therewith when two parts are in position. The upper end of the wide portion 30 of the plate j is made to fit into the enlarged portion of the opening between the sides h thereof and its rear end l is also shaped to the same contour as the rear of the heel so that when the two plates are in position as shown 35 at Fig. 6 they completely cover the upper surface of the main,—or detachable,—portion of the heel. The inner and smaller end m of the plate j is provided with a number of,—say, two,—holes n corresponding 40 with the pins i with which they engage.

On reference to Figs. 3 and 6 of the drawings it will readily be seen that the width of the plate j between the edges k is the same as between the sides h of the opening in plate c and the turned up portions f of the plate c are made practically a continuation of that width in order to form a slide for guiding the enlarged portion k of plate j , while the smaller end of the plate 45 j is about the same width as the distance between the two parallel edges f of the first named plate c . In the upper surface of the portion m of plate j is formed, by stamping or otherwise, a tapering or other shaped recess o for the reception of the pointed end p of a detaching tool q , as shown at Figs. 14 and 15. The inner or horizontal shaped end r of the plate j is also turned upward slightly at an angle so as to permit of the 50 inner ends as shown at Fig. 10 more readily sliding over the tapering pins i when the two parts of the heel are being fixed in position. The plate j is fixed, as shown at Fig. 9, to the inner surface of the detachable top lift b , when that portion is required 55

to be made to slide from the rear for attaching it to the main portion of the heel which is fastened to the sole of the boot in the usual manner. The surface of the breast of the top portion of the heel is, in this case, 70 suitably recessed to receive the angular portion r and the recessed portion o . If desired the front end of the plate j may also be shaped to the contour of the breast of the heel. 75

When the top piece b is pushed forward, as at Fig. 9, from the rear to the breast e of the heel, the broad portion of the second plate j will then pass and slide under the narrow portion f of the recess in the first 80 plate c , whereby a slide is formed until the second plate come to the portion c^1 of the plate c which is not cut away, then the tongue or reduced portion m of the second plate j will rise over it, as shown at Fig. 85 10, and the portion m acts, when the plates are in position, as a fulcrum, the rear portion of the plate j simultaneously acting as a lever. The top piece b is then continued to be pushed forward until the holes n in 90 the front portion m of plate j pass over and engage with the fixed tapering pins i of plate c when the holes are wedged tightly on the same and the sliding plate j held fast so that it cannot move either backward or 95 forward until raised by the tool q . When fixed in the position shown at Fig. 6 the two parts will not readily separate unless a suitable tool, such as q , provided with a pointed end p , and with or without a projection s on each side thereof is inserted into the recess o between the two plates for raising the reduced portion of the plate j clear of the pins i , then the tongue or reduced portion of plate j can be lifted over the 100 tapering pins i and the top lift and plate j attached thereto can be pushed backward toward the rear of the heel so that it can readily be made to slide out of position. When the two plates are locked together any 105 appreciable sidewise shake of the plate is obviated by the wide portion k of the second plate j passing under the longitudinal edges f of the remaining rear portion of the plate c and the rear plain and level portion 110 of plate j is held in position by the sides h of the enlarged portion of the opening in the rear of the plate c fixed to the main portion of the heel. 115

By the rear portion of the second plate j being placed in the opening h and the portion m of the slide j as just described pushed forward until the tapering pins i have entered the holes n of plate j the said pins will then retain and securely hold the front 120 and reduced portion m of plate j in position, and the necessity of having the said plates made with mathematical accuracy is then avoided, as the tapering of the pins i ,—and making them smaller at the top 125 130

than the diameter of the holes *n*,—provides for and takes up any movement in the plate *j* as it is pressed on to the pins.

In some cases where it is found necessary 5 to slide the detachable top piece *b* on to the main portion *a* of the heel from the breast *e* of the heel instead of from its rear as previously described for Fig. 9, all the alteration that is required is to reverse the 10 position of the plates *c* and *j*, that is to say, in this instance the plate *c* will be fixed to the detachable top piece *b* as shown at Figs. 12 and 13 and the plate *j* to the main portion of the heel, as shown at Figs. 11 and 13. 15 In this case the main portion of the heel will be suitably recessed to receive the inclined portion *r*, Fig. 10, and tapering recess *o* of the plate *j*. In all other respects the two plates are the same and act in a similar 20 manner to that described for Figs. 1 to 9 when the top piece is pressed forward from the rear *e* of the heel on to the main portion thereof in the direction of arrow 2.

It will be readily understood that although 25 a detachable top piece *b* is described and illustrated as being placed on to the main portion of the heel, yet it is to be distinctly understood that if so desired the plates *c* and *j* may be respectively fixed on to the sole 30 of the boot and on to the inner surface of the heel so that a heel could be attached by the means herein described to the sole of the boot instead of being a fixture as is ordinarily the case.

35 What I claim is:—

1. A device for securing a detachable portion of a boot or shoe heel to its main portion comprising an attaching plate made in two parts of different sizes arranged to 40 partly fit within each other and adapted when placed together to partly slide under and partly over each other, said smaller part being in the form of a lever, said larger part having a fulcrum supporting the smaller 45 part and adapted to bind the parts together.

2. In a device for securing a detachable portion of a boot or shoe heel to its main portion the combination of a plate shaped to the contour of the heel and provided with a 50 central recess extending from the rear to within a suitable distance of its front portion, said recess being enlarged at its rear, and the edges of the smaller portion of the recess being turned slightly at an angle to 55 form a parallel slide, with a second plate of the same width as and arranged to fit into the enlarged portion of the recess, said second plate being shaped at its rear end in conformity with the heel and slidably en- 60 gaging beneath the marginal bent edges of the recess of the first part, and outstanding

tapering pins carried upon the forward end of the first plate, said second plate having a reduced forward end provided with openings receiving the pins to lock the plates together. 65

3. In a device for securing a detachable portion of a boot or shoe heel to its main portion the combination of an attaching plate made in two parts of different widths 70 arranged to partly fit one with in the other and under and partly over each other, the smaller plate being perforated at the front and arranged to fit at the back into an opening at the rear of the larger plate for completing its contour, and tapering pins fixed to the front of the larger plate and engaging in the perforations of the smaller plate to lock the plates together. 75

4. The combination with a fixed heel section, of a detachable heel section, a plate attached to one of said sections, and a second plate attached to the other of said sections, one of said plates being smaller than the other and adapted to fit partly within 80 and partly over the other whereby said fixed and said detachable sections are secured together.

5. In combination, a receiving plate having a longitudinal opening in one end and 90 having the marginal edges of the opening bent out of the plane of the plate and providing a forward cross-piece to the plate, a sliding plate fitting in the opening in the receiving plate and having its edges bent 95 out of the plane of the sliding plate for engagement beneath the bent marginal edges of the receiving plate, said sliding plate having a reduced prolongation resting against the cross-piece of the receiving plate, and 100 interlocking pins carried between the plates, the interfitting bent edges of the plates binding the prolongation against the receiving plate.

6. The combination with a fixed and a detachable heel section, interlocking attaching plates carried upon the opposite faces of the sections and having interfitting edges binding the plates together, an elongated portion on one plate having perforations and yielding 105 engaging against the opposite plate, and outstanding pins carried upon the second plate for interlocking engagement with the perforations in the elongated portion of the first plate, said elongated portion having 110 a recess in its outer end adapted to receive an instrument to release the plates. 115
